UNITED STATES PATENT OFFICE.

HARRY H. PRATLEY, OF KANSAS CITY, MISSOURI.

SOUND-PRODUCING DEVICE.

1,251,918.

Specification of Letters Patent.

Patented Jan. 1, 1918.

Application filed January 10, 1916. Serial No. 71,212.

To all whom it may concern:

Be it known that I, HARRY H. PRATLEY, a citizen of the United States, residing at Kansas City, in the county of Jackson and 5 State of Missouri, have invented certain new and useful Improvements in Sound-Producing Devices; and I do declare the following to be a full, clear, and exact description of the invention, such as will enable others 10 skilled in the art to which it appertains to make and use the same, reference being had to the accompanying drawings, and to the letters and figures of reference marked thereon, which form a part of this specifi- 15 cation.

My invention relates to sound producing devices and has for its principal object to provide a simple and inexpensive device whereby the sound recorded on a disk or 20 like record may be reproduced.

In accomplishing this object I have provided improved details of structure, the preferred forms of which are illustrated in the accompanying drawings, wherein:—

25 Figure I is a perspective view of a sound reproducing device constructed according to my invention.

Fig. II is an elevation of the same, the record and a part of the handle member 30 being in section to better illustrate the clamping of the record on the handle.

Fig. III is a detail perspective view of the needle slide.

Fig. IV is a longitudinal section of the 35 same.

Fig. V is an elevation of a part of the slide rod, showing a modified form of amplifier.

Referring more in detail to the draw- 40 ings:—

1 designates a handle member which may be of any suitable shape and material, but having a flat top 2 provided with a socket 3 that is threaded to receive the left hand 45 threaded shank 4. Fixed on the shank 4, at a distance from the threaded end thereof, is a stop boss 6, which is of sufficiently greater diameter than the post to form a contacting surface thereabout for bearing against a 50 disk record when the latter is applied to the handle, as will presently be described, and which preferably comprises a sleeve, the outer edge of which forms a seat 7 upon which a vibrator rod collar 8 is adapted for 55 support.

The post 4 extends outwardly beyond the

collar and sleeve and at its outer end is provided with a wing or like handle 9 which is anchored to the post, preferably by means of a pin 10, so that it will not turn thereon 60 and whereby the post may be threaded into the handle 1 or held when the handle is threaded onto the post. The collar 8 is loosely mounted on the post and adapted for freely seating on the seat 7, and surrounding the post and bearing against the flange 11, on the wing handle 10, and on the upper face of the collar is a coil spring 12 which is adapted for yieldingly retaining the collar 8 to its seat and for providing limited freedom of movement on the post, so that it 65 may rise or rock thereon.

The collar 8 carries a rod 14 which may be of a suitable length to extend beyond the edge of the record on the handle member, 70 and slidably mounted on said rod is a sleeve 15, the fit of the sleeve on the rod being sufficiently loose to allow the sleeve to slide freely over the rod but sufficiently close to transmit vibrations from the sleeve to the 80 rod.

Suspended from the sleeve 15 is a barrel 16, having a transverse socket 17 therein that extends upwardly at an angle in order to seat a needle 18 in proper position for 85 following grooves in a round record, and extending longitudinally through the barrel and into the socket, is a threaded bore 19 that is adapted for carrying a set screw 19' whereby the needle 18 may be firmly fixed 90 in the barrel. Attached to the barrel and collar 15 and extending at substantially a right angle to the needle is a shoe 20 which is adapted for travel along the face of a record to assist in supporting the rod 14 95 and for retaining the angle of the needle relative to the record in order to insure a proper reproduction of sound.

In order to amplify the reproduction of sound from the record I provide for carrying an amplifier, such as a piece of parchment or the like, indicated in dotted lines in Fig. I, by mounting a post 22 on the collar 15 so that vibrations from the needle are conducted through the mounting collar and 100 post 22 to the amplifier.

As will presently be more fully described, the sound is reproduced by means of the needle 18 and instead of the record being moved along the needle, as in the usual type 110 of reproducers, I move the needle along the record by swinging the rod 14 about its

central mounting. In order however to insure a proper travel of the rod I place a weight 24 on the end of the rod, and preferably anchor the weight adjustably by means of a set screw 25, so that it may be moved along the rod and fixed in any desired position thereon.

The weight may consist of a member corresponding to that shown in Fig. V wherein 10 it comprises an amplifier 26 of any suitable shape or material, and which is preferably provided with a neck 27 through which a set screw 28 is extended into engagement with the carrying rod.

15 In using the device, assuming that the parts are constructed and assembled as described, a record disk 27, having the usual central aperture is moved onto the post 4 so that the shank will project through the 20 disk aperture. The handle is then screwed onto the shank until its seat bears against the bottom of the disk and binds the disk firmly between the end of the handle and the boss 6. A needle is then placed in the 25 barrel 16 and fastened by means of the set screw and the sleeve moved along the rod so that the needle may be located in an outer groove of the record. If the weight on the 30 rod 14 comprises the amplifier, no additional member for accomplishing this purpose is required, but a piece of paper or parchment, or other like material may be placed on the post 22 in order to amplify the sound.

With the parts arranged as described, the 35 operator grasps the handle 1 firmly and rotates it in order to throw the arm 14 around the disk, so that it travels on its pivotal mounting on the post and moves the needle through the spiral groove in the disk. 40 When the needle moves through the groove it engages the projections thereon so that the needle is vibrated from the record and the vibrations conducted from the needle to the sleeve and rod, and thence to the amplifier, so that the record is reproduced and sounded.

By mounting the sleeve 15 slidably on the rod the sleeve may move inwardly automatically as the needle follows the groove, and 50 by mounting the collar 8 loosely on the post 4 a certain freedom of movement is permitted that will prevent possible damage or stiffness in the operation of the device, the spring 12 holding the rod to position 55 and permitting the free rotation of the rod and limited movement thereof. As the threads 4 on the post 3 are left-hand threads and as the needle is moved about to the right, it is apparent that the friction of the 60 needle on the disk will not tend to loosen the disk from its mounting but on the contrary will tend to tighten the same, so that there is no danger of the disk becoming loosened to interfere with the proper operation of the needle.

The collar 15 and the parts directly connected therewith are of such light weight that they are subject to slight interference from centrifugal force, but, on the contrary may move inwardly, against such force, under the guiding influence of the needle in the record groove.

It is further apparent that by providing the barrel 16 with the shoe 20 the needle is stabilized during its movement in order to 75 produce an even and clear reproduction.

Having thus described my invention, what I claim as new therein, and desire to secure by Letters-Patent, is:—

1. The combination with a disk holder, of 80 a needle carrying device rotatably mounted relative to the disk holder, and yielding means for retaining the said device in functional position.

2. The combination with a handle member, of means for clamping the disk to the handle member, a rod pivotally mounted on 85 said means, and a collar slidably mounted on the said rod and adapted for supporting a needle, the said collar comprising a member 90 for wiping the disk during travel of the rod.

3. The combination of a handle member, of means for clamping a disk to the handle member, a rod pivotally mounted on said 95 means, a collar slidably mounted on the rod and adapted for supporting a needle, and means on said collar for carrying an amplifier.

4. The combination with a handle member, of means for clamping a disk to the handle member, a rod pivotally mounted on said means, a collar slidably mounted on 100 said rod and adapted for supporting a needle, and a weight adjustably mounted on 105 said rod.

5. The combination with a handle member, of means for clamping a disk to the handle member, a rod pivotally mounted on said means, a collar slidably mounted on 110 said rod and adapted for supporting a needle, and a spring for urging the collar to functional position.

6. The combination with a handle, of a post removably mounted on the handle and 115 adapted for clamping a disk thereto, a collar pivotally mounted on the post, a rod on said collar, a sleeve slidably mounted on the rod and adapted for carrying a needle, and a weight on said rod.

7. The combination with a handle, of a post removably mounted on the handle and adapted for clamping a disk thereto, a collar pivotally mounted on the post, a rod on said collar, a sleeve slidably mounted on the rod 125 and adapted for carrying a needle, and a weight adjustably mounted on said rod.

8. The combination with a handle, having a screw threaded socket, of a post having a threaded shank adapted for seating in said 130

socket, a protuberance on said post adapted for binding a disk against the handle, a collar loosely mounted on the post and seated on said protuberance, a member on the outer 5 end of the post, a spring surrounding the post and bearing against said member and against the collar, a rod on said collar, and a sleeve slidably mounted on the rod and adapted for carrying a needle.

10 9. The combination with a handle, having a screw threaded socket, of a post having a threaded shank adapted for seating in said socket, a protuberance on said post adapted for binding a disk against the handle, a collar loosely mounted on the post and seated 15 on said protuberance, a member on the outer end of the post, a spring surrounding the

post and bearing against said member and
against the collar, a rod on said collar, a
sleeve slidably mounted on the rod and
adapted for carrying a needle, and a shoe
on said sleeve adapted for wiping engage-
ment with the disk when the device is in op-
eration. 20

10. The combination with a handle, of a 25
post removably mounted on the handle and
adapted for binding a disk thereto, a rod
pivotally mounted on the post, means slid-
ably mounted on the rod for carrying a nee-
dle, and an amplifier adjustably mounted on 30
the rod.

In testimony whereof I affix my signature.

HARRY H. PRATLEY.
